United States Patent Office

Des. 233,059

Patented Oct. 1, 1974

233,059

MOWER-CONDITIONER

Bobby Gene Sawyer and Ralph August Gerhardt, Ottumwa, William Frederick Hertzog Purcell, New York, and James Mervyn Conner, Mamaroneck, N.Y., assignors to Deere & Company, Moline, Ill.

Filed Oct. 30, 1972, Ser. No. 302,140

Term of patent 14 years

FIG. 1

FIG. 2

FIG. 3

FIG. 4

FIG. 5

FIG. 1 is a right front perspective view of a mower-conditioner showing our new design.

FIG. 2 is a perspective view as seen from the left front.

FIG. 3 is a perspective view as seen from the right rear.

FIG. 4 is a perspective view as seen from the left rear.

FIG. 5 is a left side elevational view.

We claim:

The ornamental design for a mower-conditioner, substantially as shown.
